FIG. 2

FIG. 3

FIG. 4

FIG. 5

FIG. 6

FIGURE 1 is a front perspective view of a facsimile transceiver, showing my new design;

FIGURE 2 is a top plan view thereof;

FIGURE 3 is an elevation as seen from the left of FIG. 1;

FIGURE 4 is an elevation as seen from the right of FIGURE 1;

FIGURE 5 is a front elevation thereof;

FIGURE 6 is a rear elevation thereof.

The characteristic features of my design reside in the specific characteristic shape of the front portion of the transceiver as best illustrated in FIGURE 1 on the drawing.

I claim:

The ornamental design for a facsimile transceiver, as shown and described.
